UNITED STATES PATENT OFFICE

ELIZABETH KENNY, OF SYDNEY, NEW SOUTH WALES, AUSTRALIA

TRANSPORT STRETCHER

Application filed March 23, 1927, Serial No. 177,790, and in Australia August 9, 1926.

This invention relates to an improved transport stretcher and is designed for the purpose of providing a stretcher combining rigidity and resiliency, also comfort and ventilation, and when necessary warmth to the patient.

The invention consists of a wooden under-frame provided with wheels, to the sides of the frame are fitted spiral compression 10 springs supporting an upper frame to which are attached boards forming the bed of the stretcher.

On to the sides of the upper frame are pivotally connected collapsible curtain frames, 15 and on to one end of the said frame double hinged collapsible curtain supports and on to the end of the frame an adjustable hinged foot board.

Curtains are attached to the sides and head 20 of the frame adapted to roll up and be fastened by straps; when unrolled they are stretched over the curtain frames.

In order that the invention may be easily understood reference is now made to the accompanying drawings in which—

Fig. 1 is a perspective view of the stretcher out of commission.

Fig. 2, perspective view showing the curtain frames erected.

Fig. 3, perspective view showing the curtain frames erected, the end curtains stretched over the end frames, the head curtain stretched over the head supports and three of the curtains stretched out prior to same being attached to the frames.

Fig. 4, detail of hinged clip to enlarged scale.

Fig. 5, elevation of one frame showing hinged clip.

Fig. 6 is a perspective view showing the stretcher entirely closed.

The reference letters serve to indicate corresponding parts in all figures.

A is an under-frame of skeleton formation and attached to which are wheels B, C is the upper frame supported on the lower frame by spiral springs D providing resiliency to the upper frame.

E are collapsible curtain frames consisting of two vertical members and a horizontal

member pivotally connected together by pivots E1, and the lower ends of the vertical members pivotally attached to the sides of the frame C by pivots E2, and when erected held in upright position by clips F, as shown in Figs. 4 and 5. These clips consist of upper and lower hinged sections, the lower sections being secured to the inner sides of the frame C by screws or the like, said upper sections being bifurcated so that when swung outwardly and upon the upper surface of the frame C they will embrace the vertical members of the collapsible frames and hold them in upright position.

G are double hinged curtain supports, G1 and G2 are the hinges, one of these supports is hinged to a bearer block H fixed to the floor of the stretcher and the other hinged to the floor of the stretcher, which permits the support hinged to the bearer block H to rest 70 on the top of the support hinged to the floor of the stretcher when said supports are folded, as shown in Figure 1. The side and head curtains when stretched over the supports hold them in position.

I is the floor of the stretcher on which rests a suitable mattress and pillow kept in position by the raised sides of the upper frame C and by straps J tacked to the sides of the said frame and buckled together.

K is a hinged foot board, the butt of the hinge attached to the end of the upper frame C, the foot board may be adjusted to any angle by the straps L fastened to the end of the rear collapsible frame, the holes in the straps fitting on to studs on the edges of the foot board, or the foot board may be laid flat on the floor of the stretcher when not in use.

The curtains may be made of any suitable fabric, M designates the side curtains and N the head curtain. The front side curtains and the head curtain may be of one piece of fabric, the sides folded over the top and rolled up together with the end curtain as 95 shown in Figure 1.

The curtains when not in use are rolled up and fastened by straps P as shown in Figure 1.

R are handles for carrying the stretcher, 100

but telescope handles as ordinarily used with stretchers may be substituted.

Minor modifications may be resorted to without departing from the spirit or scope of the invention.

In using this stretcher more especially in outback country districts, make shifts are avoided, such as a door or fence palings to provide for a rigid bed for the mattress, which when used eliminates resiliency, also dispensing with projecting handles which assists in moving the stretcher in restricted areas, ventilation can also be obtained when desirable by rolling up any of the curtains.

What I do claim as my invention, and desire to secure by Letters Patent is:

1. A transport stretcher comprising a lower rectangular skeleton frame, an upper frame having a floor therein, supported on the lower frame, collapsible side frames pivotally attached to the sides of the upper frame adapted to be moved to an upright position and held in such position by hinged clips attached to the sides of the upper frame, roll curtains on the side edges of the upper frame adapted to be unrolled and attached to said side frames, a foot board hingedly connected to one end of said upper frame, straps on the collapsible side frame adjacent to said foot board for maintaining said foot board in position, double hinged curtain supports on the other end of the upper frame adapted to be moved in an upright position, a roll curtain on said end adapted to be unrolled and attached to said double hinged curtain supports in their upright position and held in such position by the over-stretched curtain, straps on the side edges and the end edge of said upper frame having the roll curtains secured thereto for maintaining the curtains in a rolled up position, and a strap on the upper frame for fastening a mattress and pillows to the floor of said frame.

2. A transport stretcher comprising a lower rectangular skeleton frame, an upper frame having a floor therein, supported on the lower frame, collapsible side frames pivotally attached to the sides of the upper frame adapted to be moved to an upright position and held in such position by hinged clips attached to the sides of the upper frame, roll curtains on the side edges of the upper frame adapted to be unrolled and attached to said side frames, a foot board hingedly connected to one end of said upper frame, straps on the collapsible side frame adjacent to said foot board for maintaining said foot board in position, double hinged curtain supports on the other end of the upper frame adapted to be moved in an upright position, a roll curtain on said end adapted to be unrolled and attached to said double hinged curtain supports in their upright position and held in such position by the over-stretched curtain, straps on the side edges and the end edge of

said upper frame having the roll curtains secured thereto for maintaining the curtains in a rolled up position, and a strap on the upper frame for fastening a mattress and pillows to the floor of said frame, and pockets disposed on said side curtains.

In testimony whereof I affix my signature.

ELIZABETH KENNY.
